UNITED STATES PATENT OFFICE

ISIDOR ROSENBLATT, OF NEW YORK, N. Y.

DESIGN FOR A LIGHTING FIXTURE OR ARTICLE OF SIMILAR NATURE

Application filed February 12, 1930. Serial No. 34,495. Term of patent 3½ years.

To all whom it may concern:

Be it known that I, ISIDOR ROSENBLATT, a citizen of the United States, residing in New York city, in the county of Kings and State of New York, have invented a new, original, and ornamental Design for a Lighting Fixture or Article of Similar Nature, of which the following is a specification, reference being had to the accompanying drawings, forming a part thereof.

Figure 1 is a perspective view of a lighting fixture showing my new design. Figure 2 is a diagrammatic view for the purpose of illustrating contour. The view from the sides and rear is similar to that shown in the drawings.

I claim:

The ornamental design for a lighting fixture, or article of similar nature, as shown and described.

In testimony whereof I affix my signature.

ISIDOR ROSENBLATT.
